ABSTRACT OF THE DISCLOSURE

Diethylaminoethyl dextran is used as an adjuvant for vaccines for active immunization to provide a new vaccine wherein a considerable raising of the immunity is achieved in the subjects vaccinated.

BACKGROUND OF THE INVENTION

Field of the invention

This invention relates to new vaccines containing adjuvants and more particularly to vaccines containing adjuvants comprising diethylaminoethyl dextran.

Description of the prior art

The necessity of coupling antigens with adjuvants in order to achieve an improved immunity, has been well known in the prior art. There are a number of adjuvants which can be used for this purpose, among which, water-in-oil emulsions and aluminum hydroxides are most frequently used.

These adjuvants, depending on the antigen which is used with them or depending on the type of animal in which the vaccine is used, give variably favorable or less favorable results. All that the above-mentioned adjuvants have in common is that they constitute a large portion of the vaccine, namely 25–50%. In addition and especially in the case of mineral oil-containing adjuvants, strong acid reactions may occur at the place of vaccination.

For these reasons, it was necessary to search for an adjuvant which:

(a) increases the immunogenic effectiveness of antigens, that is to say the antibody formation and the immunity, and do this both in view of its beginning and its duration;

(b) is relatively slightly toxic, so that only slight reactions to vaccination occur, which lead to no permanent changes at the places of vaccination, which is particularly of importance in the case of slaughter animals;

(c) is fully effective in case of all animals;

(d) occupies little space in the vaccine volume, so that practically the entire vaccine consists of nothing but antigen. The consequence of this is, that either the dose of vaccine can be greatly reduced or that, in the case of weak antigens, considerably more antigen can be introduced with one dose of vaccine, than was possible hitherto; and

2

(e) no expensive and cumbersome manipulations are needed for production of the vaccine.

The adjuvant and resulting new vaccine of the present invention satisfy these requirements.

SUMMARY OF THE INVENTION

It is accordingly one object of the present invention to provide an adjuvant and resulting new vaccine which meets the above enumerated requirements.

10 A further object of the present invention is to provide diethylaminoethyl dextran as an adjuvant to antigen solutions in vaccines.

Further objects and advantages of the present invention will become apparent as the description thereof proceeds.

15 In satisfaction of the foregoing objects and advantages the present invention provides a new vaccine in which diethylaminoethyl dextran (DEAE-D) is added directly as an adjuvant to the antigen solution.

20 DESCRIPTION OF PREFERRED EMBODIMENTS

The present invention relates to a new vaccine in which diethylaminoethyl dextran (DEAE-D) is added directly as an adjuvant to the antigen solution. Besides a considerable increase in the antibody formation and prolonged persistence of the antibody titers, this new vaccine also causes a considerable raising of the immunity in the case of the subjects vaccinated, as compared with application of the antigen alone.

30 The proportion of the diethylaminoethyl dextran adjuvant to be employed according to the present invention is about 5 to 250 mg. of DEAE-Dextran per ml. of inoculation serum and more preferably about 50 mg. of DEAE-Dextran per ml. of serum.

35 The following procedure has been found to provide good results in adding the diethylaminoethyl dextran in substance. In practicing this procedure, a proper quantity of the DEAE-Dextran adjuvant, within the above limits, is placed in a suitable vessel. In the case of antigens sensitive to acid, the acid pH value of the DEAE-D is balanced out through the addition of a proper buffer substance. It turned out to be most practical to use for this purpose a saturated tris solution. However equivalent buffering substances may also be employed. In the case of a starting

40 pH of the antigen solution of 7.8–8.0, it is necessary to add approximately 2.25 ml. of saturated tris solution per 10 g. DEAE-D in order to obtain a pH value of 7.4–7.6 in the finished vaccine. If one wishes to obtain either higher or lower pH values, then correspondingly more or less

45 tribuffer is to be added. The mixture of DEAE-Dextran and the added buffer substance is heated in an autoclave for 20–30 minutes at 110° C. to 120° C. for the purpose of sterilization. After complete cooling, the antigen solution is added to the solidified DEAE-Dextran and the mixture is kept at least 48 hours with occasional shaking at a suitable temperature. In this time, the DEAE-Dextran usually is dissolved. After this is the case, the vaccines are

50 shaken for 1 hour and they are then allowed to stand until their use, once more for at least 24 hours at a suitable temperature.

55 One can use as antigens all substances which are immunogenically effective in a purified, partly purified or

nonpurified state. Any possibly existing toxic or virulent characteristics of the antigens are decreased or destroyed prior to the addition of DEAE-Dextran to the point that the antigens become harmless for the subject to be inoculated. The antigens may be added individually or in multiples. The DEAE-Dextran may also be added to vaccines together with other adjuvants, for example, Al(OH)_3 , saponins, oil adjuvants, etc.

As an example in the application of DEAE-Dextran containing vaccines, the following immunization experiment in the case of a pig with a vaccine consisting of the inactivated virus of the mouth and hoof disease and DEAE-Dextran as adjuvant is presented.

The experimental system selected is particularly well suited to present proof of the effectiveness of DEAE-Dextran containing vaccines, since it is quite generally known that it is difficult to immunize pigs with hitherto customary hoof and mouth disease vaccines. The protection of such immunization usually extends to only 4 weeks and the titers of the neutralizing antibodies during this time are very low and will reach values of 1:50 only in individual cases.

In this experiment, 15 pigs were immunized with vaccines which consisted of ethylethyleneimine inactive mouth and hoof disease virus of the type O, and 50, 100, and 200 mg. of DEAE-Dextran per ml. The immunization took place subcutaneously using 10 ml. doses.

Serum samples of these animals were then obtained at various times and were investigated with regard to their content of neutralized antibodies. Twelve weeks after vaccination, a test infection of the animals inoculated was made by adding control pigs infected with mouth and hoof disease and without protective immunization in the pens.

The results of these experiments are shown in Table 1 following.

Table 2 present the results of an immunization experiment with guinea pigs. A mouth and hoof disease virus suspension of type O, heat inactivated at 37°C . was used for the manufacture of the vaccines. Different quantities of DEAE-D were added. In each instance 0.5 ml. of the pertinent vaccines were inoculated intramuscularly at 4 places in the guinea pigs.

Another experiment was carried out with an inactivated virus of the "infectious bovine rhino-tracheitis." This virus belongs to the group of viruses containing desoxyribonucleic acid, while the mouth and hoof disease virus is assigned to the group of viruses containing ribonucleic acid. In this experiment too, the adjuvant effectiveness of DEAE-D was confirmed.

From the results mentioned, it becomes clear that diethylaminoethyl dextran (DEAE-D) in combination with an antigen, completely fulfills the initially set requirements of an antigen. Thus the combination is effective as:

(a) It considerably increases the immunogenic effectiveness of antigens as well as the rapid formation of antibodies in the pig (4th day after vaccination), as well as the high antibody titers in the case of pigs and guinea pigs, and the long persistence of the antibodies, as well as the almost 100% immunity which inoculated pigs show 12 weeks after vaccination.

(b) It is not very toxic, for 14-16 weeks after vaccination no noteworthy changes could be found in the case of animals as was shown by experiments with pigs, guinea

(c) It works equally well in the case of various kinds of animals as was shown by experiments with pigs, guinea pigs, rabbits and mice.

From the prescription for manufacture given above, it becomes clear, moreover, that DEAE-D also fulfills the requirements made in the beginning under points (d) and (e), that is to say, as far as space is concerned it is of no object in the total volume of the vaccine and no cumbersome manipulations are required in the case of manufacture of the vaccine.

TABLE 1

¹ Reciprocal value of the serum titer after days ("T" or weeks "W").

² Test infection of the inoculated animals by adding the control animals Nos. 127, 128.

³ Body temperature prior to test infection.

⁴ Highest body temperature in the course of 1-7 days after test infection.

⁵ Died after circulatory failure.

⁶ Sloughed because of considerable emaciation.

⁷ Formation of aphthae on 1 claw.

⁸ Formation of aphthae on 2 claws.

⁹ Formation of aphthae on 3 claws, the animal died because of myocarditis caused by mouth and hoof disease.

5
TABLE 2

The formation of neutralizing antibodies in the case of guinea pigs after inoculation with mouth and hoof disease vaccines with varying quantities of DEAE-D

DEAE-D per ml. vaccine	ND ₅₀ values of the serums 4 weeks after vaccination
5 mg.	¹ 1:15-1:113- ² 1.63
15 mg.	1:64-1:280-1:151
30 mg.	1:195-1:1,080-1:451
45 mg.	1:235-1:1,500-1:937
60 mg.	1:300-1:1,500-1:674
Control ³	Negative-1:31-1:10

¹ Extreme values.

² Mean value from the individual titers of 60 guinea pigs.

³ Inactivated virus without adjuvant.

What is claimed is:

1. Vaccines for active immunization of pigs containing an effective subcutaneous or intramuscular dose of inactivated hoof and mouth virus antigens and as an adjuvant an effective amount of, diethylaminoethyl dextran to elevate the antibody titer.
2. Vaccines according to claim 1 wherein said antigens are immunogenically effective in a purified, partly purified or nonpurified state.
3. Vaccines according to claim 2 wherein said diethyl-

6

aminoethyl dextran adjuvant is present in an amount of about 5 to 250 mg. per ml. of inoculation serum.

4. Vaccines according to claim 3 wherein said diethylaminoethyl dextran adjuvant is present in an amount of about 50 mg. per ml. of inoculation serum.

5. Vaccines according to claim 3 wherein said antigens are sensitive to acid and the pH value of the diethylaminoethyl dextran is balanced out by the addition of a buffer substance.

10 6. Vaccines according to claim 5 wherein sufficient buffer is added to obtain a final pH of 7.4-7.6 in the finished vaccine.

7. Vaccines according to claim 6 wherein the buffer substance is saturated tris solution.

15 8. Vaccines according to claim 7 wherein the buffer solution and diethylaminoethyl dextran are heated at 110° C. to 120° C. prior to addition to the antigen.
